METAL TREATING FURNACE AND METHOD

Henry A. Drefein, Chicago, Ill.

Application February 11, 1936, Serial No. 63,366

7 Claims. (Cl. 266—5)

This invention relates to annealing furnaces and has more particular reference to a furnace for heat treating metal sheets, strips, coils, plates, and similar members under desired atmospheric 5 conditions in the furnace and to a novel method of annealing.

An important object of the invention is the provision of a novel and an improved furnace of the movable bell type.

10 Another important object of the invention is the provision of a movable work enclosing shield or shell within such a furnace, so constructed and arranged that desired atmospheric conditions may be established and maintained therein.

15 A further important object of the invention is to provide a pressure stabilizing or compensating seal for preventing, or at least minimizing, the infiltration of air or other undesirable gases or mixtures thereof into the work enclosing shell 20 if or when, during the operation of the furnace, a pressure differential occurs between the inside and the outside of the shell.

An additional important object of the invention is to provide such a seal for minimizing interference 25 between convection currents in the work enclosing shell by the occurrence of a pressure differential between the inside and the outside of the shell, whereby to promote the efficient heat distribution and circulation within the shell.

30 Another important object of the invention is to provide work supporting means constructed and arranged to promote a uniform distribution of heat by convection in the work enclosing shell, whereby work on the supporting means in the shell will be heat treated on all sides.

35 Further important objects of the invention include the provision of a direct-fired annealing furnace of the movable bell type; a movable work enclosing shell within and spaced from the furnace to provide a combustion chamber therebetween; a base for accommodating the furnace and the work enclosing shell; a seal between the base and the furnace; a pressure regulating seal between the base and the work enclosing shell; 40 work supporting means on the base in the shell providing heat passages under the work for uniformly distributing the heat about the work; burner means arranged in the combustion chamber to direct the flame downwardly, and at such a level that the discharge pressure of the burner 45 means will project the flame to adjacent the base for supplying maximum heat at the bottom of the combustion chamber and permitting the heat then to circulate about the work enclosing shell;

50 such burner means in the combustion chamber 55

being adjustable for providing the proper amounts of heat in the furnace at the beginning, during, and at the end of the heat treatment operation; and a novel method of annealing in a movable furnace with a work enclosing shell therein by 5 establishing desired atmospheric conditions in the annealing chamber, sealing that chamber to maintain such conditions, and directly firing the furnace.

Other objects of the invention will be apparent 10 from the following description, and from the accompanying drawings, in which similar characters of reference refer to similar parts throughout the several views.

In the drawings,

Fig. 1 is a plan view, partially in section, of a furnace embodying the features of the invention;

Fig. 2 is a side elevational view partially in cross section, of the furnace shown in Fig. 1;

Fig. 3 is an end elevation, partially in section, 20 of the novel furnace;

Fig. 4 is a diagrammatic sectional view of the furnace shown in the preceding figures, and illustrates the assembly of the novel furnace;

Fig. 5 is a fragmentary detail of a slightly 25 different form of seal from that shown in Fig. 2;

Fig. 6 is an elevational view partially in section, of one of the burners employed in the novel furnace, and showing certain details of construction and assembly;

Fig. 7 is an elevational view of the inlet end 30 of the burner shown in Fig. 6;

Fig. 8 is a cross section taken substantially along the lines 8—8 of Fig. 6;

Fig. 9 is a cross section taken substantially 35 along the lines 9—9 of Fig. 6; and

Fig. 10 is a fragmentary cross section taken substantially along the lines 10—10 of Fig. 8.

Illustrative of the invention, the novel furnace of the invention as shown in Figs. 1 to 3, may be 40 briefly and generally described as comprising a base 15, work supporting means 16, on the base for supporting, for example, metal sheets 17 to be treated, a work enclosing shell or shield 18 for providing a treating chamber 19 about the work, 45 and a movable furnace 21 of the bell type, arrangeable on the base 15 about, and in spaced relation with, the shell 18 for providing a combustion chamber 22 about the shell.

The base 15 is constructed to provide a foundation 23 of suitable construction, a foundation covering 24 of any suitable insulating or refractory material, and a retaining structure preferably of metal sheets 25, channels 26, and corner or angle members 27, arranged about the sides 55

of the base and extending to a level above that of the insulating base covering 24. Such a base may, as shown in Figs. 1 to 3, be rectangular in top plan view and is adapted to carry thereon, if desired, furnace aligning pins or studs 23 fixed in diagonally opposite corners of the base 15 and extending upwardly therefrom for engaging in apertured brackets 28 correspondingly positioned on the movable furnace 21 during the assembly 10 of the furnace on the base.

The work supporting means 16 may be generally rectangular in plan, of smaller plane dimensions than the base, and is constructed and arranged centrally thereof. It comprises a mounting layer 31 of insulating or refractory material carrying thereon a metal pan 32 with upstanding sides 33 spaced inwardly of the metal sheets 25 and providing or defining therewith a trough or channel 34 circumscribing the sides 33 of the pan 32 for carrying an appropriate sealing agent 35. In and centrally of the pan 32 a plurality of spaced upstanding members 36 of insulating or refractory material carry a work supporting metal plate 37. The members 36 are arranged to 25 extend transversely of the pan 32 beginning and ending at positions respectively spaced inwardly from the end sides 33 of the pan and are of such length that their opposite ends are spaced inwardly from the longitudinal sides 33 of the pan. 30 Thus a trough or channel 38 is provided between the sides of the pan 32 and spaced members 36 for carrying a suitable sealing agent 39.

The work enclosing shell 18 is of metal construction with side walls 41, end walls 42, and a 35 top or roof 43, and is provided with eyelet means 44 to facilitate positioning the shell on the base and removing it therefrom. The dimensions and configuration of the shell 18 are such that the side walls are receivable in the channel 38 between the sides of the pan 32 and the members 36.

For cooperating with the sealing agent 39 to provide a seal about the lower edges of the shell 18 between the treating chamber 19 and the combustion chamber 22, the lower marginal portions 45 of the side and end walls 41 and 42 are constructed to provide one (see Figs. 1 to 4) or more (Fig. 5) sealing spaces or passages 45 receivable in the channel 38. Such a passage or such passages 45 may be provided at the lower peripheral 50 margin of the shell 18 by a flange-like member conforming to the configuration of the shell and connecting therewith above the lower edges of the side and end walls. Such flange-like member is provided with an outwardly extending portion 55 46 and, connecting therewith, a depending portion 47 spaced from the walls of the shell 18 to provide one passage 45 or, if desired, a plurality of spaced depending portions 49 (Fig. 5) connecting with the outwardly extending portions 46 and spaced from the walls of the shell 18 to provide a plurality of the passages 45.

The movable furnace 21 comprises two side walls 49, two end walls 51, and a roof or crown 52 constructed of a suitable refractory material 65 in a metal casing 53 that is reinforced by a suitable frame or superstructure 54. In the roof or crown 52 are provided a plurality of flue openings 55, and suitable eyelet means 56 is constructed on the superstructure or frame 54 to facilitate 70 positioning the furnace 21 on the base and removing it therefrom. The dimensions and configuration of the movable furnace 21 are such that the walls 49 and 51 thereof are adapted to seat in the trough or channel 34 for cooperating 75 with the sealing agent 35 to provide a seal about

the bottom of the movable furnace between the inside and the outside of the combustion chamber 22.

A plurality of individual burners 57 are arranged in the combustion chamber 22 above the bottom thereof and project through the side walls 49 of the furnace 21. At their outer ends the burners 57 are provided with suitable connections 58 communicating with a fuel supply manifold 59 and with connections 61 communicating 10 with a supply pipe 62 for supplying air for combustion to the burners. Those burners 57 are respectively associated at their ends in the combustion chamber 22 with individual hoods 63 of suitable refractory material and secured in any 15 desired manner over the burners along the walls 49 in the combustion chamber to provide a downwardly extending passage 64 for each burner, communicating at its lower end with the combustion chamber. 20

In determining the position of the burners 57 above the bottom of the combustion chamber 22 in the direct-fired, movable furnace, the burner discharge pressure is considered and the burners are arranged at such a height that the pressure 25 employed will carry the flame to adjacent the bottom of the combustion chamber for supplying the maximum heat where it is most needed. If the burners are too near the bottom for the pressure employed, the sealing agent 39 may be disturbed with the result that combustion products or gases may pass from the combustion chamber into the treating chamber and deleteriously affect the work. If, on the other hand, the burners are 30 too high, the heat at the bottom of the combustion chamber may be considerably less than the heat at the top thereof with the result that all of the work is not uniformly heated. I have found that the best results are obtained when the burners are arranged, with reference to the discharge pressure thereof, at such a distance above the bottom of the combustion chamber 22 that the burner flames will just barely reach the bottom of the combustion chamber. 35

While the burners 57 may be of any suitable 45 construction, the ends of the invention are best served by employing multi-nozzle, adjustable burners of the type illustrated in Figs. 6 to 10. Such burners have the additional advantage of facilitating the bringing of the furnace up to 50 proper heat conditions after which the heat supplied may be adjusted to a value for maintaining such conditions. Each such burner 57, accordingly, comprises an outer air supply fixture 65, an inner fuel supply fixture 66, and an assembly 55 head or fixture 67 provided with a closure member 68 at its outer end. That assembly head 67 serves as a mounting for the air supply fixture 65 and the fuel supply fixture 66. For that purpose the assembly head has an adapter fixture 69 60 connectible in communication with one of the connections 68 and extending through the closure member 68 for connection at its other end to the fuel fixture 66; and communicating connecting portions 71 and 72. The connecting portion 71 of each assembly head is connectible to one of the connections 61, and the connecting portion 72 is connected to the air fixture 65. 65

The air fixture 65 is provided near its inner or discharge end with a plurality of discharge apertures or orifices 73 of the same or different sizes and, respectively aligned therewith are a plurality of fuel discharge apertures or orifices 74 of the same or different sizes in the fuel fixture 66. By such a construction, fuel supplied to the 75

fuel fixture 66 may be discharged through one or more of the orifices 74, mixed with air supplied to the air fixture 65, and the combustible mixture discharged through one or more of the orifices 73. For adjusting the fuel and air supplied by the novel burner, a slideable valve member 75 is arranged in the air fixture 65 between the inner wall thereof and the outer wall of the fuel fixture 66. That valve member 75 is constructed to provide a surface 76 for closing an orifice 73 in the air fixture 65 and a surface 77 for closing an orifice 74 in the fuel fixture 66 when the valve member is moved longitudinally of the burner in one direction, and to open those orifices when the valve member is moved in the opposite direction.

Valve operating means in the form of a reciprocable rod 78 is secured as at 79 to the valve member 75 and extends outwardly therefrom, longitudinally of and between the coaxial fixtures 65 and 66, through the closure member 68, outside of which the rod 78 is guidably supported in a bracket 81 suitably secured to the assembly head 67 and is provided with means 82, for limiting the reciprocable movement of the rod. Each hood 63 may be provided with a bayonet slot 83 for cooperation with a lug 84 on each burner for holding the hood in position.

For establishing the desired atmospheric conditions in the treating chamber 19, I provide means, diagrammatically illustrated at 85 in Figs. 1 to 4, which provides communication between the inside and the outside of the chamber. Means, diagrammatically illustrated at 86, provides communication between the inside and outside of the sealing spaces or chambers 45 for establishing the proper atmospheric conditions therein for maintaining the atmospheric conditions in the treating chamber.

In operation, the sheets 17 or other work to be treated is placed on the work supporting plate 37 of the work supporting means 16, and an overhead crane is employed to lower the work enclosing shell 18 and the movable furnace 21 to their respective positions on the base 15 with the shell 18 inwardly of and spaced from the furnace 21, thus forming the treating chamber 19 inside of the shell and the combustion chamber 22 between the shell and the furnace. In thus assembling the novel furnace, the sealing chambers about the lower marginal portions of the shell 18 are positioned in communication with the means 86 for establishing the proper atmospheric conditions in the sealing chambers, and the sealing agent 38, for example, sand, may be tamped in the channel 39 about the outer depending walls of the sealing chambers. The lower edges of the furnace 21 seat in the channel 34, and the sealing agent 35 is employed to seal between those edges and the bottom of the channel.

After the furnace has been assembled on the base 15, the means 85 and 86 may be employed for providing the desired atmosphere in the treating chamber 19 and in the sealing chamber 45 thereabout, for example, a suitable gas such as coke producer gas, deoxidized natural gas, or any atmosphere for protecting or desirably affecting the work, may be supplied to or established in the treating and sealing chambers by the means 85 and 86. When the desired atmospheric conditions have been reached in the treating chamber, the means 85 may be adjusted in any well known manner to reduce or to terminate its action in supplying gas to or establishing other de-

sirable atmospheric conditions in the treating chamber, whereupon the means 86, cooperating with the sealing chamber 45 and the sealing agent 39, effectively seals off the treating chamber for maintaining the atmospheric conditions 5 established therein.

With such sealing means about the treating chamber, if a pressure differential between the outside and the inside of the treating chamber is caused by, for example, temperature variations, variations of pressure in the combustion chamber 22 due to combustion conditions therein, or to changes in the air and/or fuel supply pressures, or whatever the cause, that pressure differential will not produce the objectionable 15 pressure oscillations about the lower edges of the shell 18, or if such pressure oscillations are produced, they will not result in a transfer of combustion gases or atmosphere from the combustion chamber into the treating chamber because 20 the atmosphere in the sealing chamber 45, being under pressure, acts first to oppose the infiltration of gas from the combustion chamber into the sealing chamber, and secondly to provide an atmosphere that protects or otherwise desirably 25 affects the work if any gas from the sealing chamber should be, by displacement from gas seeping therein from the combustion chamber, transferred into the treating chamber.

During the first step of the heat treatment, 30 the burners 57 along opposite sides of the movable furnace 21 may be operated with all of the discharge orifices 73 and 74 open until the furnace is brought up to the desired temperature, whereupon the reciprocable rods 78 may be 35 pushed inwardly to the position shown in Fig. 6 to move the slideable valve members 75 to a position for closing a sufficient number of the aligned orifices 73 and 74 for adjusting the heat supply to a value sufficient to maintain the desired heat 40 conditions in the furnace.

It will be seen that the flames from the burners 57 will be directed downwardly toward the bottom of the combustion chamber for supplying heat where it is most needed, and the heat thus 45 supplied may circulate in the combustion chamber about the shell 18 for heating the work therein. As the atmosphere in the treating chamber within the shell 18 is thus heated by the direct-fired furnace 21, heat distribution may be effected by convection under the work between succeeding spaced members 36 and on all sides of the work for effective and efficient heat treatment thereof.

Thus, by directly firing the furnace, heat 55 transfer losses are minimized. That desirable result is made possible by the novel and effective seal between the combustion and treating chambers, which insures the maintenance of proper atmospheric conditions in the treating 60 chamber without, or at least with only a minimum of, contamination by gases having a deleterious effect upon the work seeping into the treating chamber. The sealing means and the direct firing thus cooperate with the novel burner 65 and the means for permitting a uniform circulation of heat in the treating chamber for efficiently heat-treating the work therein.

While I have illustrated and described a preferred embodiment of my invention, many modifications may be made without departing from the spirit of the invention, and I do not wish to be limited to the precise details set forth but desire to avail myself of all changes within the scope of the appended claims.

Having thus described my invention, what I claim as new and desire to secure by Letters Patent of the United States is:

5. 1. A furnace comprising a base, a work enclosing shell mounted on said base and providing a treating chamber in the shell, a shell enclosing bell removably mounted on said base about and in spaced relation with said shell for providing a combustion chamber in said bell about said shell, a burner in a side wall of said bell and having adjustable outlet means in said combustion chamber and having inlet means outside of said bell, and means extending outside of said bell for adjusting said adjustable outlet means.
10. 2. A furnace comprising a base, a movable work enclosing shell thereon providing a treating chamber about the work and having a sealing chamber adjacent the base and surrounding the shell, a movable shell enclosing bell on the base about and in spaced relation with the shell for providing a combustion chamber in the bell about the shell, and a plurality of multi-nozzle burners in the combustion chamber.
15. 3. A furnace comprising a base, a movable work enclosing shell thereon providing a treating chamber about the work and having a sealing chamber adjacent the base and surrounding the shell, a removable shell enclosing bell on the base about and in spaced relation with the shell for providing a combustion chamber in the bell about the shell, a plurality of burners in said combustion chamber, adjustable means in said combustion chamber for adjusting each said burner, and means outside of said combustion chamber for adjusting said adjustable means.
20. 4. In a furnace of the movable bell type, a treating chamber, a combustion chamber around said treating chamber and separated therefrom, burner means having a plurality of burner outlets in said combustion chamber to direct flames, and burner outlet control means in said combustion chamber and operable from outside thereof for controlling said burners.
25. 5. In a furnace, a base, a movable outer bell, an inner bell spaced from said outer bell to provide a combustion chamber therebetween, and burner means in said combustion chamber above said base and directed downwardly for providing a plane that extends barely to the bottom of said combustion chamber.
30. 6. In a furnace of the movable bell type, a treating chamber, a combustion chamber separated therefrom and surrounding said treating chamber, and downwardly directed burner means arranged in said combustion chamber so that with reference to the discharge pressure of said burner means the flames therefrom will barely reach the bottom of the combustion chamber.
35. 7. In a furnace of the movable bell type, a method of heat treatment which comprises providing a treating chamber in and separated from a combustion chamber, forming a sealing chamber around the bottom of the treating chamber and between it and the combustion chamber, establishing a work affecting atmosphere in the sealing chamber, directly firing the combustion chamber, and extending the flame downwardly barely to the bottom of the combustion chamber.

HENRY A. DREFFEIN. 35
